UNITED STATES PATENT OFFICE.

THOMAS G. BOWERS, OF NEW HAVEN, CONNECTICUT.

CORSET.

Application filed June 26, 1925. Serial No. 39,748.

This invention relates to corsets, and more particularly to a garment of this character which is designed to give proper support to the abdomen and the organs therein, and at the same time be comfortable to the wearer and provide for the greatest possible freedom of movement. To properly support the abdomen it is necessary that the corset be capable of exerting upward pressure upon the organs in the lower part thereof, so as to give the proper posture to the body and insure the weight of the abdomen being properly carried by the hips. My improved corset is, therefore, designed so that the upper edge thereof reaches a little above the waist-line of the wearer, while the lower portion extends downwardly about the hips and at the front below the abdomen. Below the front supporting portion of the corset is secured an elastic section which, while properly confining the flesh and connecting the sides of the garment, which are longer than the front portion, will not interfere with the free movement of the limbs of the wearer, nor interfere with the assumption of a sitting position.

One object of my invention is to provide an improved garment of the character described, which will give adequate and proper support to the abdomen and at the same time will provide for the necessary freedom of the movement of the limbs of the wearer.

Another object of my invention is to provide a corset which will assure the proper posture of the body of the wearer and extend downwardly about the hips and thighs, and at the same time will provide for the necessary freedom of movement of the limbs.

A still further object of my invention is the provision of a corset provided with an uninterrupted front portion or plate, laced to the body of the garment at both side edges thereof, this front portion extending downwardly below the abdomen and having therebelow an elastic section of a width substantially equal to that of the front section.

To these and other ends the invention consists in the novel features and combination of parts to be hereinafter described and claimed.

In the accompanying drawings:

Fig. 1 is a side view of a corset embodying my improvements, as it appears upon the wearer;

Fig. 2 is a front view of the corset; 55
Fig. 3 is an inside view of the corset extended, and

Fig. 4 is a sectional view on line 4—4 of Fig. 3.

As shown in the drawings, the preferred 60 embodiment of my invention which I have selected to illustrate and describe, comprises an inelastic body portion 10, comprising a number of sections 11, between which extend the usual stays 12. The stays are inserted 65 in stay pockets 13, as is customary, these pockets extending throughout the length of the body portion of the garment. The stays themselves, however, as shown in Fig. 3, are generally shorter than the garment, and 70 while they extend to the upper edge thereof, they terminate above the lower edge of the corset, so that the lower part of the garment will be more flexible.

The center of the back of the garment is 75 shown by the line 14, and upon each side gussets 15 of elastic material may be inserted so that this part of the garment may be stretched to some extent.

The body portion of the garment is provided at one end with a stay section 16 to which are secured clasp members 17, designed to be engaged with cooperating clasp members 18 upon the stay section 19. In use, the garment will ordinarily be fastened 85 and unfastened by means of these clasp members, and as shown in Fig. 1, the garment opens at one side substantially in line with the arm and shoulder.

The front portion of the corset comprises 90 a front section 20 of inelastic material. At each edge this section is provided with eyelets 21 through which laces may be passed to be engaged with the eyelets 22 in the body portion 10 of the corset, and the eyelets 23 95 in the clasp section 19. This front section is slightly higher at its central portion, as shown at 24, than at the side edges thereof, and is also lower at the central portion, as shown at 25 than at the laced edges.

Below the front inelastic portion 20 is secured an elastic section 26 of substantially the same width as the part 20. The upper edge of this elastic section is shaped or tapered to correspond to the lower edge of the part 20, and likewise, the lower edge of the elastic section is reversely shaped so that the latter section is considerably wider at the

edges than at the central portion thereof. It will be obvious that with this arrangement, the front section of the corset including the elastic portion 26, is relatively long 5 adjacent the side edges where the laces are secured so that it extends downwardly to some extent over the limbs of the wearer and properly confines the flesh, and is shorter at the center front of the body to avoid the 10 inconvenience which might be occasioned if it were longer at this point.

The stay pockets 27 and 28 at the side edges of the front section 20 are extended downwardly throughout the length of the 15 elastic section 26, so as to provide material of greater strength for the lace eyelets.

Flaps or shields 29 and 30 are secured respectively to the back section 10 of the garment and the stay section 19, these shields 20 extending forwardly below the laces at each side of the front part of the garment, as shown in Fig. 2, to properly confine the flesh at this point and to keep the clothing of the wearer from wrinkling when the corset is 25 laced. These shields are provided with stays 31, extending in a horizontal direction, which stays tend to hold the shields flatwise on the body so as to prevent any bulkiness which might occur by reason of their becoming 30 doubled or wrinkled. The front hose supporters 32 and 33 are sewed to the lower ends of the shields 29 and 30, while the rear hose supporters 34 and 35 are sewed to the lower ends of the stay pockets upon the body portion 35 of the garment.

It will be apparent that by the provision of a continuous unbroken section at the front of the garment, with laces at both sides thereof, that this front section may be drawn 40 to properly fit the body when the corset is laced, so that an upward pressure will be applied to the abdomen and at the same time this section may be properly positioned at the exact front center line of the body without varying the location of the clasp sections, which should properly be positioned 45 below the arm. At the same time, the elastic section 26 across the front of the garment serves to properly keep the flesh confined 50 and yet does not interfere with the necessary freedom of movement which should be allowed, nor with the assumption of a sitting position by the wearer. The side laces may be adjusted so that the weight of the abdomen 55 will be properly carried to insure the correct posture of the wearer, and once fitted to the body the corset may be readily fastened in place and removed by means of the side clasps.

While I have shown and described a preferred embodiment of my invention, it is to be understood that the same is not to be limited to all the details shown but is capable of modification and variation within

the spirit of the invention and the scope 65 of the appended claims.

What I claim is:

1. A corset comprising a main section and a front section, said front section being adapted to extend continuously across the 70 front portion of the body of the wearer and having its edges connected to the main section at the sides of the garment, and said front section comprising an upper inelastic portion and a lower elastic portion, said portions being coextensive in width and secured together along the meeting edges thereof, said inelastic portion having its lower edge carried down further at the center than on the sides, and said elastic portion being 75 longer at its side edges than at the intermediate portion thereof.

2. A corset having a body section and a continuous unbroken front section connected thereto and adapted to cover the front portion of the body of the wearer, said section comprising an inelastic part extending downwardly to the lower abdomen of the wearer, the central portion of said part being carried further down than the sides, and an elastic 80 part secured below the first named portion and being substantially co-extensive in width therewith.

3. A corset comprising a rear portion and a continuous unbroken front portion adapted to be laced at both edges to the rear portions, shields each secured at one edge to the rear portion and having their free edges designed to extend beneath the adjacent edges of the front portion so as to lie beneath the laces, and hose supporters secured to said shields, said front portion having an upper inelastic part extending down to the abdomen of the wearer, and a lower elastic 100 part coextensive in width with the upper part and designed to exert an upward pressure on the abdomen.

4. A corset comprising a rear portion and a front portion adapted to be laced at both edges to the rear portion, shields each secured at one edge to the rear portion and having their front edges designed to extend beneath the adjacent edges of the front portion so as to lie beneath the laces, and hose supporters secured to said shields, said front portion having an upper inelastic part extending down to the abdomen of the wearer and a lower elastic part coextensive in width with the upper part, said inelastic part being carried down lower at the center of the lower edge than at the sides thereof and adapted by the pull of the elastic portion thereon to exert an upward pressure on the abdomen.

In witness whereof, I have hereunto set 125 my hand this 24th day of June, 1925.

THOMAS G. BOWERS.
